LONG-REACH STAPLING MACHINE OR SIMILAR ARTICLE

John J. Power, Westbury, and Nathaniel M. Olney, New
York, N.Y., assignors to Swingline Inc., Long Island
City, N.Y., a corporation of New York

Filed Oct. 14, 1968, Ser. No. 13,959

Term of patent 14 years

Int. Cl. D19—02

U.S. Cl. D74—1

FIG. 1 is an isometric view of a long-reach stapling machine or similar article showing our new design.

FIG. 2 is a top plan view thereof.

FIG. 3 is a side elevational view thereof.

FIG. 4 is a front elevational view thereof.

FIG. 5 is a rear elevational view thereof.

We claim:

The ornamental design for a long-reach stapling machine or similar article, as shown.
